United States Patent Office.

GEORGE GUY, OF BAY CITY, MICHIGAN.

Letters Patent No. 80,165, dated July 21, 1868.

IMPROVEMENT IN STEAM-GENERATORS.

The Schedule referred to in these Letters Patent and making part of the same.

TO ALL WHOM IT MAY CONCERN:

Be it known that I, GEORGE GUY, of Bay City, in the county of Bay, and State of Michigan, have invented a new and useful Improvement in Preventing Boiler-Explosions; and I do hereby declare that the following is a full, clear, and exact description thereof, which will enable those skilled in the art to make and use the same, reference being had to the accompanying drawings, forming part of this specification.

This invention relates to an apparatus for insuring the safety of steam-boilers from explosion, on account of a deficiency of water therein; and it consists in arranging a valve and seat on the crown-sheet of the fire-box and in the steam-space of the boiler, and operating them by a weight, in such a manner that when the water in the boiler falls to a dangerous point, the valves will be opened, one of which will discharge steam into the fire-box and the other will discharge steam into the atmosphere, as will be more fully described hereinafter.

Figure 1 represents a vertical longitudinal section of a steam-boiler with my safety-apparatus attached, the section being through the line *y y* of fig. 2.

Figure 2 is a vertical cross-section through the line *x x*.

Similar letters of reference indicate corresponding parts.

A represents the shell of the boiler.

B is the fire-box.

C is the steam-dome.

D represents a stuffing-box on the boiler, through which the rod E passes. This rod is turned so as to form an elbow within the boiler, as seen at *f*. To the end of this elbow there is a rod jointed, as seen at *g*. To the end of *g* there is a weight, *h*.

I is a crank, which is attached to a valve-shaft, to which are connected (by arms) two valves, *J* and *k*, formed by two arcs of circles.

The seat *i* of the valve *J* is supported by the crown-sheet of the fire-box, with an aperture, *i'*, for discharging steam downward into the fire-box. The other valve-seat is supported by the dome, and is in connection with a steam-pipe, *L*, through which steam may be discharged upward through the dome and into the atmosphere, as seen in the drawing.

m indicates the ordinary water-level in the boiler, which may be considered the point of absolute safety, as the crown-sheet *n* is covered thereby.

In this condition the weight *h* is submerged or under the surface of the water, where it will remain while there is a safe supply of water in the boiler, and where about one-third of its weight is buoyed up by the water. When the water in the boiler falls below the weight, it acts upon the valves (through the crank *I*) with increased power and with its full weight, as it is no longer buoyed up by the water.

This additional power is sufficient to move the valve and open the ports which communicate with the fire-box, thus discharging steam and extinguishing the fire. At the same time, steam is blown off through the pipe *L*, and through a whistle, if desired.

By this arrangement, all danger from explosion, in consequence of low water in the boiler, is avoided. The valve *k* may be employed or not, as may be deemed advisable.

I do not claim the use of a float or of a weight in a steam-boiler, for indicating the height of water, as I am aware that it is not new; but

What I claim as new, and desire to secure by Letters Patent, is—

1. The aperture *i*, in the crown-sheet *n*, and the valve *J*, when arranged and operated substantially as and for the purpose described.

2. In combination with the valve *J*, arranged as described, the valve *k*, substantially as and for the purpose set forth.

The above specification of my invention signed by me, this 28th day of April, 1868.

GEORGE GUY.
